DESIGN FOR A LADY'S SCARF

Toby Katzman, née Masstab, and Abraham M.
Katzman, Long Beach, N. Y.

Application January 4, 1941, Serial No. 97,801

Term of patent 3½ years

To all whom it may concern:

Be it known that we, Toby Katzman, née Massstab, and Abraham M. Katzman, both citizens of the United States of America, and both residing at Long Beach, Long Island, county of Nassau, State of New York, have invented a new, original, and ornamental Design for a Lady's Scarf, of which the following is a specification, reference being made to the accompanying drawing, forming a part thereof.

The drawing is a plan view of a lady's scarf showing the new design.

We claim:

The ornamental design for a lady's scarf, substantially as shown.

TOBY KATZMAN, NÉE MASSTAB.
ABRAHAM M. KATZMAN.
